DESIGN FOR A COMPOTIER OR ARTICLE OF SIMILAR NATURE

Charles L. Fordyce, New York, N. Y., assignor to
Pitman-Dreitzer & Co., Inc., New York, N. Y.,
a corporation of New York

Application January 1, 1945, Serial No. 117,210

Term of patent 14 years

(Cl. D36—2)

To all whom it may concern:

Be it known that I, Charles L. Fordyce, a citizen of the United States of America and a resident of New York, in the county of New York and State of New York, have invented a new, original, and ornamental Design for a Compotier or Article of Similar Nature, of which the following is the specification, reference being had to the accompanying drawing, forming a part thereof.

Figure 1 is an elevational view of a compotier showing my new design;

Figure 2 is an elevational view of the same taken at right angles to the disclosure of Figure 1;

Figure 3 is a sectional view taken along line 3—3 of Figure 1; and

Figure 4 is a sectional view taken along line 4—4 of Figure 3.

I claim:

The ornamental design for a compotier or article of similar nature, substantially as shown.

CHARLES L. FORDYCE.
